UNITED STATES PATENT OFFICE

2,502,927

DEVICE FOR PREVENTING THE FORMATION
OF ICE ON CONDUCTOR RAILSHarry Chanter, Harrow, England, assignor of
one-half to Kilstrost Manufacturing Company
Limited, Newcastle upon Tyne, EnglandApplication January 26, 1948, Serial No. 4,356
In Great Britain February 5, 1947

2 Claims. (Cl. 191—62)

1

In electric traction systems in which the electric motor or motors which drive a vehicle are supplied with current from one or more conductor rails engaged by conductor shoes on the vehicle, difficulty has been experienced in certain climatic conditions due to the formation of ice on the surface of the conductor rail or rails, which wholly or partially insulates the rail or rails and thus prevents proper contact being made therewith by the shoes.

The main object of the present invention is to provide means for overcoming or minimizing the said difficulty, and more particularly, to provide for the application of anti-freezing liquid to conductor shoes for application thereby to a conductor rail. A further object is to provide a device for this purpose which is of small overall dimensions, and is capable of being readily set in or out of operation.

According to the present invention, a device for applying anti-freezing liquid to conductor shoes for application thereby to the conductor rails of an electric traction system comprises a container for the anti-freezing liquid adapted to be so mounted that its upper surface is traversed by the conductor shoes, a roller mounted in said container, spring means urging said roller upwardly towards a position in which it projects through an opening in the upper surface of the container, and externally operable means for urging the roller downwardly into the container and retaining it in a lowered position.

The spring means may comprise a pair of blade springs each connected to one end of a spindle carrying the roller, the roller being located in the casing solely by the said springs, and the externally operable means may comprise a rotary member provided with two arms each acting on one of the blade springs.

The invention is hereinafter described with reference to the accompanying drawings, in which—

Figure 1 is a side elevation, partly in section, of one form of device according to the invention;

Figure 2 is a section on the line 2—2 of Figure 1; and

Figure 3 is a plan view of the device shown in Figure 1, part of the cover being broken away.

Referring to the drawings, the device comprises a container 10 having a base, sides and ends of mild steel sheet secured together by welding, the base 11 being wider than the container itself to provide external longitudinal flanges 12. The container, when in position for use, is secured by studs 13 and nuts 14 to mild steel bars 15 ex-

2

tending between the spaced ends 16 and 17 of sections of a conductor rail, the bars 15 being welded at their ends to the under surfaces of the rail sections. A copper strip 18 also extends between the rail ends, and is welded to them, to carry the electrical current between the rail ends.

The container 10 is closed at the top by a sheet-metal lid 21, having lugs 22 at its sides which fit over the sides of the container and are secured thereto by set screws 23. Along the centre of the lid, and welded thereto, is a thick metal strip 24 having the same width as the heads of the rails 16 and 17, the arrangement being such that, when the container is in position, the upper surface of the strip 24 is substantially continuous with the upper surfaces of the rails. A slot 25 extending through both the main lid 21 and the strip 24 forms an opening in the top of the container adjacent one of its ends. A roller having a metal hub 26 on which is mounted a circumferentially grooved rubber tire 27 is carried on a spindle 28 extending into bearings formed by sleeves 31 inserted in eyes 32 formed on the ends of two blade springs 33 the other ends of which are secured by studs 34 and nuts 35 to the base of the container, at the end of the latter remote from the opening 25. The blade springs 33 are so set that they urge the roller 26, 27 upwardly, and of such length that the roller, when urged upwardly, passes into the slot 25, the upper portion of the roller projecting through the slot. Stops 36 mounted on the underside of the lid limit the upward movement of the roller.

A shaft 37 journalled in the side walls of the container carries a pair of arms 38, 39 each co-operating with one of the blade springs 33. One end of the shaft projects to the outside of the container, and is fitted externally thereof with an arm 41, so that the shaft can be rocked by movement of the arm 41. The arrangement is such that in one position of the shaft the arms 38, 39 bear downwardly on the blade springs 33, 33 so as to depress the roller into the container, and hold it in the depressed position as shown in chain dotted lines in Figure 1, whilst in another position the arms 38, 39 are clear of the springs and allow the roller to rise to the position in which it is shown in full lines in Figure 1. A stop 42 may be provided on the wall of the container to locate the arm 41 in the position in which the arms 38, 39 depress the springs 33, 33, and a spring loaded detent 43 may be mounted in the arm 41 to engage with depressions in the

side of the container when the arm 41 is in either of its extreme positions.

When conditions are such that formation of ice on the conductor rails is likely to occur, the roller 26, 27 is released from its depressed position so that it projects through the slot and the conductor shoes of any vehicle passing along the track with which the conductor rail is associated engage and rotate the roller. Anti-freezing liquid in the container is thus picked up by the roller and applied to the conductor shoe, by which it is applied in turn to the surface of the conductor rail, thus preventing or minimizing the formation of ice on the said rail.

What I claim is:

1. A device for applying anti-freezing liquid to conductor shoes for application thereby to the conductor rails of an electric traction system, comprising a container for anti-freezing liquid, means for mounting the container between spaced portions of a conductor rail, a top to said container forming a continuation of the surface of the conductor rail upon which the conductor shoes bear, an opening in said top surface, a roller mounted in said container, a spindle carrying said roller, a pair of blade springs each connected to one end of said spindle, said blade springs constituting the sole means for locating the roller in said casing, a rotary member mounted in said casing, two arms provided on said rotary member and each acting on one of said blade springs, and means external to said casing for rotating said rotary member to a position in which said arms engage and depress said blade springs to position the roller wholly within the casing.

2. A device for mounting between spaced por-

tions of a conductor rail of an electric traction system for applying anti-freezing liquid to conductor shoes and thereby to the conductor rail, comprising at least one steel bar welded to the undersurface of said rail so as to extend across the gap between the spaced portions, a container for anti-freezing liquid having a depth equal to the depth of the conductor rail, means for securing said container to said bar, a top to said container forming a continuation of the surface of the conductor rail upon which the conductor shoes bear, an opening in said top surface, a roller mounted in said container, spring means urging said roller upwardly towards a position in which it projects through the opening, and a copper bar extending across the gap between the spaced portions of said conductor rail and welded to the undersurfaces of said portions, said copper bar serving to carry the electric current across said gap.
